UNITED STATES PATENT OFFICE.

JOSEPH DUBOIS, OF ECHO, OREGON.

SHOE-STRETCHER.

1,248,290.

Specification of Letters Patent. Patented Nov. 27, 1917.

Application filed July 24, 1917. Serial No. 182,482.

To all whom it may concern:

Be it known that I, JOSEPH DUBOIS, a citizen of the United States, residing at Echo, in the county of Umatilla and State of Oregon, have invented new and useful Improvements in Shoe-Stretchers, of which the following is a specification.

This invention relates to boots and shoes, and more especially to lasts having separate heel blocks; and the object of the same is to produce a last whose parts are capable of connection with the operating shaft or staff in such manner that the boot or shoe may be stretched laterally or longitudinally, or both, and to the desired degree within limits.

Further objects will appear from the following specification and claims, reference being had to the accompanying drawings forming part of the same and wherein:

Figure 1 is a side elevation of this device ready for use excepting that the toe block and the heel block are detached and removed slightly from their proper position.

Fig. 2 is a plan view of the toe block, the operating mechanism, and one wing or part of the body swung outward from said mechanism, and a horizontal section of the other part of the body through its cam groove, the section being carried through the heel block and its connection with the hinge.

Fig. 3 is a vertical longitudinal central section through all parts with the nearer half or wing of the body entirely removed.

Fig. 4 is a perspective detail of the swivel in the operating mechanism, showing the wedge slightly dropped out of position where it connects therewith.

Fig. 5 is a perspective view of the rear end of the body portion, showing the channels alongside the leaves of the hinge, and Fig. 6 is a corresponding perspective view of the forward end of the heel block showing the lips which engage said hinge-leaves.

This improved shoe stretcher is a last made in members which are separable from each other and from the operating mechanism and therefore which may be used selectively. One member is the toe block, and in the complete article I will provide several of these members of various sizes. Another member is the heel block, also provided in several pieces of various sizes. The third and principal member is the body, made in two parts or wings hingedly connected with each other at their rear ends. These also

may be provided in sizes, although perhaps one size will answer for most boots or shoes by the application of patches as will be explained. Ordinarily, I prefer to manufacture my device in about three sizes—large, medium, and small—each size having perhaps two or three toe blocks and two or three heel blocks, but using the same body portion; and the purchaser by buying one of each size and its appropriate pieces or blocks will have on hand a last or stretcher for almost any boot or shoe which needs attention. The several blocks and the parts or wings of the body are preferably of wood, the patches or attachments may be of leather or metal, and the other portions are by preference metal; and the exact details and proportions and sizes of parts are not essential to the present invention.

Coming now to the specific description of details and referring by reference numerals to the accompanying drawings, the body portion is made up of two halves, wings, or parts 1 and 2 which are complementary of each other and shaped about as shown, each preferably having one or more recesses as at 3 for the insertion and removal of a pad whereby the contour may be changed at will. The use of these pads for enlarging a last or stretcher at points whereof the foot of the wearer necessitates, is well known in the art and needs no elaboration here. I have shown the toe blocks (described below) as provided with "bunions" which are usually convex metal plates having stems insertible in holes bored in the parts of a last, and obviously the several parts could have appropriate holes for attachment of these devices when necessary. Often, too, the shoe-maker tacks on patches or pads of leather or the like, and for this purpose the blocks are usually of wood. By this and other means irregularities in the shape of the foot may be filled out by additions to the last at appropriate points, and these irregularities are not to be considered matters of size which I take care of by providing each outfit with several toe blocks and several heel blocks as suggested above. The body portion of the last is divided centrally and longitudinally to produce the two wings whose inner meeting faces may be flat, and in each of said faces I provide a cam groove inclined upward and rearward from the toe end of the wing and intersected by a transverse hole 6 near its rear end for a pur-

pose yet to appear. The working faces of grooves converge near the toe ends of the wings, and away from a hinge 7 whose leaves connect the flat rear ends 8 of the 5 wings. Said ends are provided along the outer edges of the hinge-leaves with upright grooves or channels 9 for a purpose yet to be described. Attached to the toe end of each wing is a curved sheet-metal guard 10 whose 10 use will be set forth.

The operating mechanism comprises a threaded shaft or staff 11 having a handle 12 at its rear end, its front end being swiveled in a block 13 which is rectangular in 15 plan view and has a forwardly extending internally threaded tube 14 as seen; and the numeral 15 designates a wedge having through its body a longitudinal open-topped channel whose walls are notched to produce 20 a recess 16 capable of closely embracing said block 13 when the wedge is in place. The edges of this wedge are adapted to travel in the cam grooves 5 in the wings 1 and 2 of the body portion of the last as the swivel 25 block 13 moves to and fro. For causing longitudinal movement of the staff 11 when turned by the handle 12, its threads engage through a nut 17 having a globular exterior and radially and diametrically oppositely 30 projecting trunnions 18 which engage the holes 6 in the two wings: however, when the wings are spread apart as their hinge permits, the holes disengage said trunnions and the entire operating mechanism can be lifted 35 out of the body of the last. At this time the swivel block 13 may be lifted out of the channel in the wedge, and in fact all parts may be disconnected for cleaning or repair. Manifestly the rotation of the staff in the 40 proper direction will cause the wedge to move forward, so that its outer edges travel up the active faces of the cam grooves 5 and spread apart the front ends of the wings, their rear ends remaining connected by the 45 hinge 7. On the other hand, rotation of the staff in the opposite direction will retract the wedge and permit the wings to collapse until their flat inner faces come into contact. Now the entire body portion may be re- 50 moved from the boot or shoe by drawing upward on the handle 12 and pulling the last out of place, as clearly understood.

The toe block 20 is of appropriate size and conformation, and is adapted to move inward and outward longitudinally beneath the sheet-metal guards 10 at the front ends of the wings. In order to effect the adjustment of this toe block, it has a threaded stem 21 which screws into the tube 14, and 55 may be run into the same to a considerable degree if the shoe is short, or may be run out of it somewhat if the shoe is longer; and subsequent forward movement of the swivel block 13 and tube 14 naturally causes the 60 forward movement of the toe block so that

the shoe is stretched longitudinally at the same time that it is stretched transversely. If longitudinal stretching is not desired, the toe block is removed entirely or is adjusted with its stem so far in the tube that its longitudinal adjustment is not sufficient to stretch the shoe. 70

The heel block 30 is of appropriate configuration to fill out the rear portion of the last, and as above suggested a complete outfit may include two or three of these blocks of different size. Its front end is channeled to overlie the knuckles and pintle of the hinge 7, and within said channel is secured a plate 31 having at its side edges upright inturned flanges or lips 32 to slidably engage the side edges of the hinge-leaves when said block is moved upward so that the lips travel within the channels 9 above described. Across the top of the block is a groove 33 through which the staff 11 extends when the parts are in operative and connected condition. This groove bisects or bifurcates the top of the block, and the arms of the bifurcation may be pierced with registering 80 holes 36 through which can be passed a pin 37 overlying the staff to hold the block from dropping out of place when the last is being inserted or removed from the shoe. When in position within the shoe, the insole 85 of the latter holds this block alined with the body portion, the same as the insole holds the toe block alined and prevents it from rotating after it has been adjusted. The heel block is not adjusted longitudinally by 90 movement of the actuating mechanism, but if it is desired to stretch the shoe longitudinally, it is accomplished by properly setting the toe block in a manner already described and then rotating the staff 11, with the result that the entire length of the last is increased as it stands within the boot or shoe, and the latter is therefore stretched longitudinally. If transverse stretching only is 95 desired, it is possible to leave off the heel block and perhaps also the toe block, or the toe block might be omitted and the heel block used simply to retain the body portion in its proper relative position within the shoe while the latter is being stretched 100 transversely. The heel block is not shown provided with holes or sockets for the insertion of stems of "bunion" and other enlargements, because ordinarily the heel of 105 a boot or shoe does not need these pads for 110 extraneous members; yet I preferably make this element of wood so that on rare occasions when a pad is necessary, it can be tacked upon as the artist will understand.

What is claimed as new is:-

1. A last whose body portion is divided longitudinally into two complementary wings having their meeting faces provided with registering cam grooves intersected near their rear ends by transverse holes, the rear 115 120 125 130

ends of said wings being provided with upright channels, and a hinge whose leaves are secured to said ends and partly overlie the said channels; combined with a threaded staff having a handle, a toe block swiveled on its front end, a wedge swivelly connected with its lower portion and moving in said cam grooves, a nut engaging the threads of the staff and having diametrically opposite trunnions removably engaged in said holes, a heel block, and a plate secured to this block and having upright inturned flanges to slidably engage the edges of the hinge leaves.

15 2. A last whose body portion is divided longitudinally into two complementary wings having their meeting faces provided with registering cam grooves intersected near their rear ends by transverse holes, the rear ends of said wings being cut off flat and provided with upright channels, and a hinge whose leaves are secured to said ends and partly overlie the said channels; combined with a threaded staff having a handle, a wedge swivelly connected with its lower end and moving in said cam grooves, a nut engaging the threads of the staff and having diametrically opposite trunnions removably engaged in said holes, a heel block grooved in its upper end to receive said staff and channeled in its front end, and a plate secured in said channel and having upright inturned flanges to slidably engage the edges of the hinge leaves.

30 3. A last having a two-part body portion, a hinge whose leaves are secured to the rear ends of the parts, said ends being channeled at the edges of the leaves, means for spreading the forward portions of said parts, and

a rotating staff for operating said means, the staff projecting between the rear ends of the parts above said hinge; combined with a heel block having its upper end bifurcated to receive said staff, means for holding the latter therein, and upright inturned flanges at the front end of the block for slidably entering the channels in the parts of the body and engaging the edges of said hinge leaves.

4. The herein described shoe stretcher comprising a body portion in two parts hingedly connected at their rear ends, means for spreading them at their front ends, and a rotating staff for actuating said means extending between their rear ends; a heel block detachably connected with said rear ends and grooved to receive said staff; a toe block, and adjustable connections between it and said spreading means whereby the block is projected longitudinally as the parts of the body are spread transversely.

5. In a shoe stretcher, the combination with a body member in two parts hingedly connected at their rear ends and having cam grooves in their meeting faces, curved guards carried by said parts and projecting beyond their front ends, and spreading mechanism including a longitudinally movable wedge mounted in said cam grooves and having a forwardly projecting internally threaded tube; of a toe block movable longitudinally beneath said guards, and a stem projecting rigidly to the rear from said block and threaded to adjustably engage said tube.

In testimony whereof I affix my signature.

JOSEPH DUBOIS.
